FIG. 3

FIG. 4

FIG. 6

FIG. 1 is a perspective view of a combined pet food bar display tray and feeder or similar article, showing my new design;

FIG. 2 is a top plan view;

FIG. 3 is a side elevational view, the opposite side being substantially a mirror image thereof;

FIG. 4 is a bottom plan view;

FIG. 5 is a front elevational view;

FIG. 6 is a rear elevational view;

FIG. 7 is a cross-sectional view, partly in elevation, taken on line 7-7 in FIG. 2; and

FIG. 8 is a cross-sectional view, partly in elevation, taken on line 8-8 in FIG. 2.

I claim:

The ornamental design for a combined pet food bar display tray and feeder or similar article, as shown and described.
